No. 630,258.

Patented Aug. 1, 1899.

P. J. McHENRY & W. T. NORTON.

REFRIGERATOR.

Application filed May 20, 1899.)

(No Model.)

THE NORRIS PETERS CO., PHOTO-LITHO., WASHINGTON, D. C.

UNITED STATES PATENT OFFICE.

PHILIP J. MCHENRY AND WILLIAM T. NORTON, OF WASHINGTON, DISTRICT OF COLUMBIA, ASSIGNORS TO JACOB NEUBERGER, OF NEW YORK, N. Y.

REFRIGERATOR.

SPECIFICATION forming part of Letters Patent No. 630,258, dated August 1, 1899.

Application filed May 20, 1899. Serial No. 717,622. (No model.)

To all whom it may concern:

Be it known that we, PHILIP J. MCHENRY and WILLIAM T. NORTON, citizens of the United States, residing at Washington, in the 5 District of Columbia, have invented certain new and useful Improvements in Refrigerators; and we do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 This invention relates to refrigerators, and has for its object the production of an improved appliance of this character which is adapted for preserving articles of food and for cooling beer or other liquor contained in 20 kegs or like vessels, the appliance to this end consisting, generally speaking, in a refrigerator provided in its upper portion with a chamber for containing ice and in its lower portion with a chamber for articles of food and be- 25 tween the chambers with a recess into which is removably inserted a box or receptacle containing a keg of beer or the like, the box with its contents in a refrigerated condition to be supplied by the brewer.

30 A feature of our invention resides in the adaptability of the refrigerated beer-box for preserving the contents of the food-chamber and in the alternate use of the ice-chamber for refrigerating the contents of the beer-box 35 and food-chamber in the event that the ice in the box becomes exhausted, it being understood that the ice-chamber is supplied with the refrigerant only when the exhaustion in the beer-box takes place.

40 Certain details of construction enter into our invention, which is set forth in detail in the following description.

Referring to the accompanying drawings, Figure 1 is a front elevation of a refrigerator 45 embodying our invention. Fig. 2 is a vertical cross-sectional view taken on line 2 2 of Fig. 3. Fig. 3 is a vertical longitudinal sectional view taken on line 3 3 of Fig. 2.

In the drawings, A denotes the casing of 50 the refrigerator, provided in its top with an opening, over which is a hinged cover a. Be-

low the opening in the upper portion of the casing is a receptacle B, preferably supported at its upper end on ledges. This receptacle constitutes a chamber into which ice may be 55 introduced through the opening. In the lower portion of the casing A is an inner casing C, forming a chamber for articles of food. The walls of the casing C are separated from the outer-casing walls to provide a space for cold 60 air. At the front of the casing A, opposite to the inner casing, is an opening closed by hinged doors a'.

Between the receptacle B and inner casing C is a recess a² to receive the beer-box D, the 65 opening to the recess being at the front and closed by a door a³, hinged to swing, preferably, upwardly and supported when raised by an arm e. The box D is slid into the recess on ways f, which support the box free of 70 the outer and inner casings to provide cold-air space. The beer-box is preferably of rectangular form and is provided at its top with a hinged cover d. In the bottom of the box are skid-blocks d' for supporting the keg or 75 receptacle G, and at the sides of the blocks are walls or partitions, the lower portion d² of each of which is fixed, while the upper portion d³ is hinged to the lower portion at d⁴ and is curved to conform to the periphery of the 80 keg. In practice, the keg being inserted, the upper partition portions d³ are brought over the keg, the partition ends lapping, and there is thus provided ample space both at the sides and above the keg for ice, which, as before 85 stated, is supplied by the brewer with the box. On one of the portions d³ is a handle d⁵, which is of sufficient height to contact with the under side of the cover d when the latter is lowered, whereby the keg is held against movement during transportation. In the front of the box and also in the door a³ are openings 90 for the faucet g. With the beer-box in place the temperature of the contained ice sufficiently cools the air circulating in the spaces 95 around the box and the chamber C to preserve the contents of the latter. If, however, the ice in the box should become exhausted, the receptacle B is supplied with ice, with the result that the beer is kept at the proper temperature and the contents of the chamber C 100 are preserved.

The receptacle B is separated from the walls of the casing A to provide cold-air space, and, if desired, air-openings (shown at b) may be provided in the receptacle-walls.

5 By our invention small kegs having a capacity of, say, two dozen pints of liquor may be provided by the brewer, who will supply the kegs as they are required ready iced. The box containing the keg when delivered 10 is placed in the refrigerator, and the consumer is thus under ordinary conditions saved from the expense of purchasing ice for preserving the contents of the refrigerator and for cooling the liquor usually supplied for household 15 use in bottles.

We claim as our invention—

1. A refrigerating appliance comprising a refrigerator having in its upper portion a receptacle for ice, and in its lower portion a 20 chamber for articles of food, and provided between the receptacle and chamber with a recess, a box removably inserted in the recess, said box adapted for holding a keg or like vessel of liquor and for containing ice,

and provided with a hole for the faucet of 25 said keg, said box and receptacle being adapted alternately for refrigeration.

2. A refrigerating appliance comprising a refrigerator having in its upper portion a receptacle for ice, and in its lower portion a 30 chamber for articles of food, said receptacle and chamber being separated from the refrigerator-wall to provide air-space, and a refrigerator beer-box, having a hole to accommodate the faucet, removably insertible in a 35 recess provided in the refrigerator between the receptacle and chamber, said box having partitions at the sides of the keg to provide ice-space, and having means for holding the keg against movement. 40

In testimony whereof we affix our signatures in presence of two witnesses.

PHILIP J. McHENRY.
WILLIAM T. NORTON.
